UNITED STATES PATENT OFFICE

2,506,513

SWEATER FRAME

Mildred Mayer, Upper Darby, Pa.

Application March 12, 1947, Serial No. 734,097

4 Claims. (Cl. 223—69)

1

This invention relates to garment driers and more particularly to driers for use with garments which, because of their material or formation or both, have a tendency to shrink or otherwise deform if dried in the usual manner.

Important objects of the invention are the provision of a device of this character which may be readily applied to and removed from the garment, which while firmly holding the garment in shape will permit even drying thereof and which may be readily produced as a pair of light readily cleansed sections molded from a plastic not subject to oxidation and inert to the ordinary cleaning agents.

These and other objects I attain by the construction shown in the accompanying drawings wherein, for the purpose of illustration, I have shown preferred embodiments of my invention and wherein:

Figures 1 and 2 are elevations of the frame sections of a drier constructed in accordance with my invention;

Figure 3 is an enlarged fragmentary elevation showing the drier applied to garment;

Figure 4 is a section on line 4—4 of Figure 3;

Figure 5 is a fragmentary elevation showing a modified form of my invention applied to a garment;

Figure 6 is a section on line 6—6 of Figure 5 and

Figure 7 is a side elevation of one of the sections, the dotted lines illustrating the flexibility thereof in a direction perpendicular to its own plane.

Referring now to the drawing, a drier constructed in accordance with my invention comprises a pair of open foraminous frames 10 and

11. In the embodiment of Figures 1 to 4 inclusive, the marginal portions 9 of the frames are perforated with round holes 8; while in Figures 5 and 6 the marginal portions 7 exhibit open grille work 6. Frames 10 and 11 are structurally reversed duplicates, being each shaped to conform to all marginal edges of the garment with which they are adapted to coat. Each frame is rigid in its own plane being braced by a foraminous brace or braces 10a and 11a respectively, to provide the necessary stiffness to resist shrinkage pull by the drying garment 4. Each frame includes a marginal rib 12 and 13 respectively, these ribs being aligned in the assembled drier and being adapted for engagement in the grooves 14 of the jaws 15 of spring clamps 16, said clamps serving to hold the frames tightly gripped upon the edge portions of the garment as shown in Figures 3, 4,

2

5 and 6 wherein the garment is indicated by reference numeral 4. The said ribs may be disposed either medially of the marginal edge portion of the frame as shown in Figures 3 and 4, or at one edge thereof as indicated at 5 in Figures 5 and 6. The confronting faces of frames are preferably relieved between the side edges thereof as shown at 17 in Figure 4 to permit free circulation of air or other drying fluid about the drying garment.

While frames 10 and 11 are rigid in their own planes they are elastically flexible in a direction perpendicular thereto as indicated by the dotted line showing of Figure 7. This enables the frames 15 to be partly separated after partial application thereof to a garment for adjustment of the garment to proper position between the frames. Such flexibility may readily be had in many of the present day plastics which are in most instances 20 free from oxidation and are inert to the substances utilized as cleaning agents. If desired one or both of the sections may be provided with a suspension means 18 by means of which the drier and the supported garment may be attached to a line or rack (not shown).

It will be obvious that a drier constructed in accordance with my invention will be of light weight and easily handled, may be readily applied to the garments for which it is designed, will effectively prevent deformation of the garment during drying thereof and may be very readily and cheaply produced. Since the constructions illustrated are obviously capable of considerable modification I do not wish to be understood as 30 limiting myself thereto except as hereinafter claimed.

I claim:

1. In a garment drier of the type described, a pair of open, unitary frames having narrow foraminous edge portions shaped to conform to and adapted to receive therebetween the marginal edges of a garment, and a plurality of clamps independently applicable to said edge portions for securing said frames to one another upon the garment.

2. In a garment drier of the type described a pair of open, unitary frames having narrow foraminous edge portions shaped to conform to 50 and adapted to receive therebetween all of the marginal edges of a garment, and a plurality of independently applicable clamps for securing said edge portions together upon the garment, the confronting faces of said edge portions being relieved 55 between the side edges thereof to permit circula-

tion of drying fluid about the encompassed portions of the garment.

3. In a garment drier of the type described a pair of frames of synthetic plastic material having narrow foraminous edge portions shaped to conform to and adapted to receive therebetween all of the marginal edges of a garment, and a plurality of independently applicable clamps for clamping said edge portions together upon the garment, said frames being rigid in their own planes and elastically flexible in planes perpendicular thereto, and the confronting faces of said edge portions being relieved between the side edges thereof to form channels for circulation of dry fluid.

4. A garment drier according to claim 1, where-
in the frames are provided with ribs extending longitudinally in the edge portions, and the said clamps are recessed for interlocking engagement with said ribs.

5 MILDRED MAYER.
